UNITED STATES PATENT OFFICE.

FRANK C. EMRICK, OF KALAMAZOO, MICHIGAN.

INSULATING MATERIAL AND METHOD OF MANUFACTURING THE SAME.

1,426,163.

Specification of Letters Patent. Patented Aug. 15, 1922.

Application filed February 17, 1921. Serial No. 445,629.

To all whom it may concern:

Be it known that I, FRANK C. EMRICK, a citizen of the United States, residing at the city and county of Kalamazoo, State of Michigan, have invented certain new and useful Improvements in Insulating Materials and Methods of Manufacturing the Same, of which the following is a specification.

10 This invention relates to an improved insulating material and method of manufacturing the same.

The main objects of this invention are:

15 First, to provide an improved insulating material from mineral wool by a felting process, the resulting product being of a resilient comparatively light character and at the same time of substantial strength permitting its use in various relations where

20 insulation is desirable.

Second, to provide an improved method of manufacturing insulating material from mineral wool by which the material may be effectively and rapidly manufactured.

25 Third, to provide an improved method of manufacturing insulating material from mineral wool whereby sheets or blocks of varying thickness may be conveniently produced.

30 Fourth, to provide an improved insulating material of mineral wool which possesses substantial resiliency and is capable of use in various relations where insulation is required.

35 Further objects, and objects relating to structural details, will definitely appear from the detailed description to follow.

I accomplish the objects of my invention by the devices and means described in the 40 following specification. The invention is clearly defined and pointed out in the claims.

A structure which is a preferred embodiment of my invention is clearly illustrated 45 in the accompanying drawing, forming a part of this specification, in which:

Fig. I is a detail view, mainly conventional, of an apparatus for carrying out my improved method or process.

50 Fig. II is a conventional side elevation of a press illustrating one step in the manufacture of my improved insulating material.

Fig. III is a conventional illustration of 55 a drier illustrating another step in the

manufacture of my improved insulating material.

Fig. IV is an edge view of one of the insulating blocks.

Fig. V is an edge view of one of the insulating blocks after the same has been pasted 60 to a sheet of paper.

In the drawing similar reference characters refer to similar parts throughout the 65 several views.

Referring to the drawing, the apparatus illustrated in Fig. I comprises a mixing tank 1 in which the mineral wool is placed and agitated in water by means of an air blast, the tank having a perforated air pipe 70 2 disposed in the bottom thereof and connected to the air tank or receiver 3 to which air is supplied under pressure from a suitable source, not illustrated.

The delivery of the air to the mixing tank 75 is controlled by the valve 4. The mineral wool is placed in the mixing tank with water containing laundry starch. I find in practice that one pound of laundry starch to twelve hundred pounds of water produces 80 satisfactory results, although the proportion of water and starch may be very considerably varied and a desirable product still produced.

The material is agitated in the tank by 85 the air blast until the fibres are well separated, that is, knots or bunches of the fibres are thoroughly broken up. The material is then transferred by means of the centrifugal pump 5 to the charging tank 6, the connection from the mixing tank to the pump 90 being the pipe 7 controlled by the valve 8, while the pipe 9 connecting the pump to the charging tank is controlled by the valve 10.

The charging tank is connected with the air receiver 3 by means of the pipe 11 which has a valve 13 therein, the pressure connection being at the top of the charging tank. The felting box 14 is connected to the 100 bottom of the charging tank by means of the pipe 15 and is controlled by the valve 16. These parts are shown mainly in conventional form.

After a charge is pumped from the mixing pump to the charging tank the valve 10 is closed and the valve 13 opened allowing the air under pressure to enter the charging tank placing the charge under high pressure therein, preferably not less 110

than twenty pounds per square inch. This may be varied, and I have employed as high as fifty-five pounds pressure. The valve 16 is then opened allowing the charge to be ejected by the air blast or force of the air against the felting screen 17.

5 A funnel 18 with discharge pipe 19 is provided for the felting box. This enables the collection of the water so that it may 10 be re-used in the mixing tank.

The screen 17 is detachably secured to the felting box. The details of the attachment are not part of this invention and are not illustrated or described herein.

15 The felted block or sheet is subjected to a press 20, shown conventionally in Fig. II, and from the press it is taken to the drier 21, shown conventionally in Fig. III.

In practice, I carry out these steps of felting and pressing by the aid of a machine specially designed for the purpose whereby the material is discharged under the pressure to the felting screens and pressed as successive steps, the machine being of the 25 general type of the machine shown in Letters Patent #891,331, June 23, 1908. The dried blocks or sheets 22 are preferably again placed in the press, which renders them quite flexible without destroying or 30 materially injuring the strength or integrity thereof.

Where it is advantageous to use the material in the form of sheets I preferably paste the felted blocks or sheets 22 upon 35 sheets of paper 23 which adapts them for various uses where asbestos paper is now quite widely used.

I am not able to state definitely the action of the starch inasmuch as the amount used 40 is so small in proportion to the mineral wool that its action is not clear. I have observed, however, that the starch has no affinity for the commercial "mineral wool" manufactured from glass, but I have 45 reached the conclusion that under the pressure the liquid carrying the starch is forced into the minute tubular fibres and into intimate contact with the same.

I have found further that high pressure 50 is necessary in order to secure the result, that is, with low pressures no material advantage is apparent from the use of the starch. The result of the use of starch under high pressure is very marked, the product being rendered much stronger and its 55 integrity greatly enhanced. At the same time the individual character of the fibres, which appear to be individually strengthened, and also the advantages as insulating 60 material are retained.

A further advantage is, when subjected to a high degree of temperature my improved insulating material is not in anywise deteriorated.

65 There is no evidence that the starch has

been affected by such high temperature, no discoloration resulting even from temperatures as high as 1800° F. The material, however, becomes considerably harder but is not vitrified by such a temperature and 70 has more structural strength without losing any of its insulating qualities.

If an amount of starch is used which would constitute a binder in the sense of an adhesive coating, as ordinarily understood, 75 such binder will char and discolor at 500° F. or 600° F.

It is in view of these considerations that I am unable to state exactly the action of the starch.

By my improved method I am enabled to manufacture the insulating material very rapidly and in relatively thin sheets or in blocks as may be desired, the process being a distinctly felting process, which, so far as 85 I am aware, has not been successfully carried out or practised heretofore with material of this character.

I have illustrated an apparatus for carrying out my method mainly in conventional 90 form as I believe the disclosure made will enable those skilled in the art to which my invention relates to carry out the same in the manner best adapted for the particular product required. The proportion of starch 95 used in the felting process may, as stated, be very considerably varied and a desirable product will be produced, the proportion stated, however, will be found very satisfactory. The quantity used should not be sufficient to destroy the individual character of the fibres.

Having thus described my invention, what I claim as new and desire to secure by Letters Patent, is:

1. The method of manufacturing insulating material from mineral wool consisting of agitating the mineral wool in water containing laundry starch by means of an air blast, felting the wool and such starch 110 containing water, subjecting to a high pressure and discharging while under such pressure upon a screen, pressing, and drying.

2. The method of manufacturing insulating material from mineral wool consisting of agitating the mineral wool in water containing laundry starch, subjecting to high pressure, and felting.

3. The method of manufacturing insulating material from mineral fibre consisting of agitating mineral fibre in water containing laundry starch, subjecting the mineral fibre and such starch containing water to pressure, and felting by discharging while under pressure upon a felting screen.

4. The method of manufacturing insulating material from mineral wool consisting of felting by the aid of water containing laundry starch.

5. The method of manufacturing insu-

lating material from mineral wool consisting of felting by the aid of water containing laundry starch in the proportion of about one pound of starch to twelve hundred dried pounds of water.

6. As an article of manufacture, an insulating material comprising mineral wool felted with the aid of water containing starch, the starch being incorporated with the mineral wool throughout but without

destroying the individual character of the fibres.

In witness whereof, I have hereunto set my hand and seal in the presence of two witnesses.

FRANK C. EMRICK. [L. S.]
